[57] CLAIM

The ornamental design for an electrolier, substantially as shown and described.

DESCRIPTION

FIG. 1 is a top view of an electrolier, showing my new design;

FIG. 2 is a front view thereof looking in the direction of arrow 2 of FIG. 1;

FIG. 3 is a bottom view thereof; and

FIG. 4 is an angular side view thereof looking in the direction of arrow 4 of FIG. 1.

The appearance of the electrolier is identical as seen from viewpoints angularly spaced at 120° about the central vertical axis.
